RADIO RECEIVING SYSTEM

Filed July 23, 1930

UNITED STATES PATENT OFFICE

VERNON C. MACNABB, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

RADIO RECEIVING SYSTEM

Application filed July 23, 1930. Serial No. 470,014.

My invention relates to tuning systems utilizable in radio receiving apparatus, and more particularly in superheterodyne systems for the reception of broadcast speech and music.

It is an object of my invention to provide, in a superheterodyne receiving system, discrimination against undesired signal frequencies in addition to that afforded by a circuit, or several circuits in cascade, tunable to the desired signal frequencies; it is a further object of my invention to procure such additional discrimination without attenuation of the desired signal input voltage, and particularly without such attenuation of desired signal input voltage as arises from increase in number of the cascaded circuits, tunable to the desired signal frequency, to the number necessary to effect comparable discrimination; and it is a further object of my invention to effect discrimination of the character aforesaid in addition to that effected by a circuit itself modified suitably to effect further discrimination against undesired signal frequency beyond that effected by tuning it to the desired signal frequency.

A selector system of this character in which marked discrimination is made between the desired and undesired signals is particularly desirable and of great advantage in superheterodyne systems in which selection of the desired signal is effected in advance of the first detector and a selective intermediate amplifier follows the detector, particularly when the adjustable tuning elements of the selector system ahead of the first detector are mechanically coupled to each other and to the frequency varying element of the oscillator, for movement in unison.

My invention resides in a system of the character hereinafter described and claimed.

For an understanding of my invention and for an illustration of some of the various forms it may take, reference is to be had to the accompanying drawing, in which:

Fig. 1 is a circuit diagram of a part of a superheterodyne receiving system embodying my invention;

Fig. 2 is a diagram of a modification.

Referring to Fig. 1, V is the first detector

of a superheterodyne receiver. In its plate circuit appears a current of beat or intermediate frequency resulting from interaction in advance of the detector of locally generated oscillations with oscillations representing the desired signal, which ordinarily is speech or music.

The plate circuit of the detector V will be understood to be coupled to one or more stages of beat or intermediate frequency amplifiers of the thermionic type (preferably sharply tuned to a narrow band of frequencies including the intermediate or beat frequency), followed by a second detector delivering signal representing current to a signal translating instrument, commonly a loud speaker, either directly or through one or more intervening audio frequency thermionic amplifiers.

The detector V is of the thermionic type having the control grid g, anode or plate a and cathode c maintained at suitable temperature by the electric heater h. In the present example the tube V is of the shield or screen grid type by virtue of the presence of the screen grid b. It shall be understood, however, that any suitable type of detector may be employed; and that when of the thermionic type its cathode may consist of a filament heated by current passed therethrough.

The local oscillations are produced by the tube O of any suitable type, in the present example comprising a filament cathode f, anode a and grid g. In its grid and plate circuits are the coils or inductances L and L₁, coupled to each other. In a resonant loop with the inductance L is a variable condenser C for determining the frequency of the oscillations generated. In the example illustrated the condenser C is in series in the loop with the condenser C₁, preferably of fixed capacity, across whose terminals are connected the input electrodes of the tube O. There may be provided also a resistance R between grid and cathode serving as a grid leak and also improving the characteristics of the oscillator system. This particular type of oscillator system is disclosed in Miller application, Serial No. 470,016, filed July 23, 1930. Or there may be employed the system of my co-

pending application Serial No. 470,557, filed July 25, 1930. Those systems have the characteristic that the frequency of the oscillations locally generated is varied substantially entirely in accord with variation of the capacity of the condenser C; that the amplitude of the oscillations is small; and that the voltage impressed upon the input of the detector V is substantially constant or varies within 10 suitably narrow limits throughout the range of frequencies of the generated oscillations.

It will be understood, however, that my invention is not limited to the particular type of oscillator employed, and any suitable 15 generally equivalent type is contemplated.

The coil L2, coupled to the coil L, is in effect the secondary of a transformer whose primary is traversed by the generated oscillations. One terminal of the secondary L2 20 is connected to the cathode of the detector V, and the other, preferably through a grid biasing resistance R1 shunted by a condenser K, to earth or ground E, which may be a common bus or conductor in or metal chassis 25 of a receiving set which may be grounded.

The electric power for the entire receiving system may be derived from any suitable source such as batteries, a commercial direct current system or a commercial alternating 30 lighting current or power system. In the example illustrated, the source of power is an alternating current circuit indicated by the conductors 1 and 2, across which is connected the primary of a transformer T having the 35 secondary S whose terminals are connected to the anodes *a* of the rectifier tube V1, having the filament or cathode *f* heated by current from the secondary S1. The uni-directional pulsating current delivered through the rectifier tube V1 is smoothed or filtered by a 40 filter system comprising, for example, inductances 3, 4 and capacities 5, 6, 7. The positive terminal of the plate circuit source is indicated at 8, while ground or terminal 9 45 is the negative pole of the source. Current from this source is supplied to the plate circuits of the tubes O, V and the other thermionic tubes of the system. The voltage effective in the plate circuit of the oscillator O 50 is determined by the resistance R2 shunted by a condenser K3. In the example illustrated the plate *a* of the first detector tube V is connected to the terminal 8, preferably 55 through a choke coil.

55 The transformer T is provided with one or more secondaries S2 supplying current for heating the cathodes of the thermionic tubes of the set.

60 The coil L2 is in effect connected in the cathode lead of the tube V extending to one terminal of a loop circuit tunable to the various frequencies of the desired signals.

65 The loop circuit comprises the secondary *s* in series with the additional inductance *s*1, that series combination shunted by the vari-

able condenser C2 for tuning the loop to the frequency of the desired signal. As indicated, the inductance *s*1 may be shunted by a condenser K1, preferably of fixed capacity. While this type of loop circuit is preferred, 70 it shall be understood that other types may be employed. This particular type is disclosed in Miller application, Serial No. 465, 603, filed July 3, 1930. It has the desirable characteristic of affording additional discrimination against signals of undesired frequencies, particularly those differing in fixed amount from the desired signal frequency, and more particularly differing from the desired frequency by twice the frequency of the 80 locally generated oscillations.

Coupled to the secondary *s* is the primary *p* in series with the inductance L3. These inductances in series are bridged by the condenser C3, variable to tune the loop so formed 85 to the desired signal frequency.

The absorption or antenna system, in which first appear oscillations representative of the signals is in the example illustrated coupled to the loop L3, *p*, C3 through the capacity K4 90 of say 7 micro-microfarads, and comprises an open antenna path of which D is the antenna proper connected to earth or counter capacity E, through the inductance L4, condenser K2 preferably of fixed capacity, and the condenser C4 variable to tune the absorption system to the undesired signal, more particularly to the undesired frequency which differs from the desired signal frequency by 95 twice the frequency of the locally generated 100 oscillations.

Assuming the system to be designed for reception of broadcast signals having a frequency anywhere within the range from 550 to 1500 kilocycles, and the beat or intermediate frequency of the superheterodyne system to be say 130 kilocycles, the frequency of the oscillations locally generated may be higher or lower than the signal frequencies by 130 kilocycles. It will be assumed that the locally generated frequency is higher than the desired signal frequency, and in such case the local frequency will vary between 680 and 1630 kilocycles as determined by the setting of the condenser C. Within the broadcast 115 range there are other frequencies which in reaction with the locally generated oscillations will also produce the same beat or intermediate frequency of 130 k. c. This causes the so-called "double spot" or "image" interference, because it is possible under the circumstances mentioned that two stations may be broadcasting at the same time signal frequencies differing by 260 k. c., both producing the same beat or intermediate frequency 125 and, therefore, causing interference. This is possible notwithstanding the selector system in advance of the first detector V is tunable to the desired signal frequency. This type of interference is particularly noticeable 130

when the undesired signal frequency is that of electro-magnetic waves radiated from a nearby or powerful broadcasting station while the desired signal is relatively weak.

- 5 The frequency of the undesired interfering signal may be higher than that of the desired signal by the aforesaid 260 k. c. It is to that undesired frequency that the absorption path is tuned by variation of the condenser C4.
- 10 When the absorption structure is so tuned to the undesired signal by the series resonance combination described, there is afforded additional discrimination against the undesired signal beyond that effected by the above described system tunable to the desired frequency. The additional discrimination arises from the fact that when the absorption structure is tuned to resonance for the undesired signal the impedance of the tuned system is
- 15 extremely low, and the voltage representing the undesired signal is extremely low, and in consequence oscillations of undesired frequency appearing in the input system are of extremely low amplitude, reducing to a minimum the "double spot" interference effect. Whatever be the amplitude of the oscillations of undesired frequency reaching the loop system tunable by the condenser 62 in spite of the discrimination by tuning to the desired signal frequency, their effect is further reduced because as to them the series resonant system s1C2 has extremely low impedance, with correspondingly decreased effect upon the grid g of the detector V.
- 20 At the same time, however, the impedance of the absorption path with regard to oscillations of the desired signal frequency is such that they will materially affect through the coupling K4 the input system of the detector
- 25 V. Throughout the frequency range to which the absorption structure is serially tuned for the undesired frequencies, the impedance of that path remains suitably high and to all intents and purposes constant for the desired signal frequencies.

A system of this character has the advantage that the oscillations of desired signal frequency are not materially attenuated, or in any event are not attenuated to anything like the degree occurring when, for discriminating to like extent against undesired signal frequencies, a sufficient number of loops tunable to the desired frequency and in cascade in advance of the input system of the detector V is employed. While attenuation caused by such number of cascaded circuits may be compensated for by adequate amplification by the intermediate frequency amplifier, there may arise undesirable tube noises occasioned by the high degree of amplification required. My system avoids such difficulty.

In brief, in accordance with my invention a high degree of discrimination against undesired signal frequencies is obtained with-

out recourse to additional loops, tunable to the desired frequency, in cascade in advance of the detector tube, which arrangement seriously attenuates the desired signal oscillations.

As indicated by the broken lines U the adjustable elements of the variable tuning devices of the selector system are mechanically coupled for adjustment in unison or by uni-control. This uni-control may, as indicated, be extended to include the condenser C of the local oscillator system whose capacity is so varied, as the aforesaid tuning devices are adjusted, that the frequency of the local oscillations always differs by the same and to the necessary extent for maintaining constant the beat or intermediate frequency.

It will be understood that the capacities of the several condensers C, C2, C3 and C4 may have as to any two or more of them, or as to all of them, the same characteristic as regards extent of change of capacity per unit of angular adjustment of their rotors. Any two or more or all of these condensers may be of the straight line capacity, straight line frequency, or straight line wave length type, or of a type having a composite characteristic.

It will be further understood that any two or more or all of these condensers may if suitable and desirable be comprised in a single unit or gang, and in such case the rotors of the different condensers may be mounted side by side upon the same shaft which is rotated for effecting the uni-control adjustment.

There is preferably included in the antenna circuit a condenser K2 which is of such value that with the condenser C4 set for the same capacity as condensers C2 and C3, the antenna circuit is always tuned in series resonance to a signal 260 kilocycles higher than the frequency of the desired signal; the condensers C2 and C3 tuning their respective circuits to the frequency of the desired signal.

In Fig. 2 is shown a modification in which there is employed an inductive coupling between the antenna or absorption structure and the selector system in advance of the tube V. In this instance there is taken a connection through the primary p_3 loosely coupled to the secondary L3. This inductive coupling is utilized in lieu of the capacitative coupling K4, Fig. 1, particularly when the antenna is of high or higher capacity than that for which the capacitative coupling is suitable to impress upon the selector system, tunable to the desired signal frequencies, voltages substantially proportional to the effective height of the antenna D. With antennas of relatively higher capacity, as aforesaid, the inductive coupling of Fig. 2 is preferred to insure impression upon the selector system tunable to the desired signals, voltages which are substantially proportional to the effective height of the antenna.

In a system of the character above described, for the broadcast range of frequencies, the inductance L4 may be about 165 microhenries; the condenser K2 may have a capacity of about 620 micro-microfarads, and the tuning condensers C2, C3 and C4 may have their capacities variable between about 50 and about 400 micro-microfarads.

I claim:

series with serially related capacities, one of which is variable and another larger than the maximum value of the variable capacity utilized in tuning, tunable to undesired signal frequencies differing from the desired signal frequencies by twice the intermediate frequency, another component of said selector system tunable to the desired signal frequencies comprising a loop including inductance and a variable tuning capacity, means for impressing upon the first detector the voltage across a terminal of said loop and a point dividing the loop inductance into components one of which in series with the variable capacity of said loop constituting a series resonance combination tunable to said undesired signal frequency, and means for inductively coupling said antenna path to said other component of said selector system.

4. A superheterodyne receiving system comprising a selector system, a first detector, an intermediate frequency amplifier, a second detector, and a local generator of oscillations whose frequency is determined by a variable capacity, said selector system comprising an antenna path including an inductance in series with serially related capacities, one of which is variable and another larger than the maximum value of the variable capacity utilized in tuning, tunable to undesired signal frequencies differing from the desired signal frequencies by twice the intermediate frequency, another component of said selector system tunable by a variable capacity to the desired signal frequencies, means for coupling adjustable elements of said variable capacities for adjusting them in unison, and means for loosely coupling said other component of said selector system to said antenna path by a small capacity. 100 105 110 115 120 125 130 135 140 145 150 155 160 165 170 175 180 185 190 195 200

5. A superheterodyne receiving system comprising a selector system, a first detector, an intermediate frequency amplifier, a second detector, and a local generator of oscillations whose frequency is determined by a variable capacity, said selector system comprising an antenna path including an inductance in series with serially related capacities, one of which is variable and another larger than the maximum value of the variable capacity utilized in tuning, tunable to undesired signal frequencies differing from the desired signal frequencies by twice the intermediate frequency, another component of said selector system tunable by a variable capacity to the desired signal frequencies, means for coupling adjustable elements of said variable capacities for adjusting them in unison, and means for inductively coupling said other component of said selector system to said antenna path.

6. A superheterodyne receiving system comprising a selector system, a first detector, an intermediate frequency amplifier, a second detector, a local generator of oscillations 130

whose frequency is determined by a variable capacity, said selector system comprising an antenna path including an inductance in series with serially related capacities, one of which is variable and another larger than the maximum value of the variable capacity utilized in tuning, tunable to undesired signal frequencies differing from the desired signal frequencies by twice the intermediate frequency, another component of said selector system tunable by variable capacity to the desired signal frequencies, and means for coupling the other component of said selector system to said antenna path, and means for mechanically coupling the adjustable elements of the capacities of the selector system and the variable capacity of said oscillator for adjusting them in unison.

7. A superheterodyne receiving system comprising a first detector, an input system therefor tunable to the desired signal frequency and including a variable condenser, an open antenna system coupled to said input system and including in series an inductance in series with a variable condenser similar to and adjustable through substantially the same range of capacity as said first condenser, a local oscillator system including a variable condenser, means mechanically coupling the adjustable elements of all of said condensers for movement in unison, an intermediate frequency amplifier, and a fixed capacity in series with said second condenser and said inductance and of such magnitude that throughout the range of movement of said variable condensers in unison, said second variable condenser, said fixed capacity and said inductance are continually in series resonance for a frequency higher than the frequency of the desired signal by twice the intermediate frequency, substantially to eliminate transfer to said input system of energy of said higher frequency.

8. A superheterodyne receiving system comprising a first detector, an input system therefor tunable to the desired signal frequency and including a variable condenser, a shunt path coupled to and in advance of said input system and comprising an inductance connected in series with a variable condenser similar to and adjustable through the same range of capacity as said first condenser, a local oscillator system having a variable condenser, means mechanically coupling the adjustable elements of all of said condensers for movement in unison, an intermediate frequency amplifier, and a fixed capacity in said path in series with said inductance and second variable condenser thereof, and of such magnitude that said path, throughout the range of adjustment of said condensers in unison, is continually tuned to series resonance for a frequency higher than the frequency of the desired signal by twice the intermediate frequency substantially to elimi-

nate transfer to said input of energy of said higher frequency.

9. A superheterodyne system comprising a first detector, an input system therefor tunable to the desired signal frequency and including a variable condenser, an open antenna system coupled to said input system and including in series an inductance in series with a variable condenser similar to and adjustable through the same range of capacity as said first condenser, means mechanically coupling the adjustable elements of said condensers for movement in unison, a local oscillator system, an intermediate frequency amplifier, and a fixed condenser connected in series with said inductance and said second variable condenser, and of such magnitude of capacity that said inductance and series connected condensers are continually in series resonance for a frequency higher than the desired frequency by twice the intermediate frequency substantially to eliminate transfer to said input system of energy of said other frequency.

10. A superheterodyne receiving system comprising a first detector, a selector system in advance of said detector comprising a path including an inductance and a variable condenser in series, and a loop tunable to the desired signal comprising an inductance and a variable condenser, similar to and adjustable through substantially the same range of capacity as said first condenser, means mechanically coupling the adjustable elements of said condensers for movement in unison, a local oscillator system, an intermediate frequency amplifier, and a fixed condenser in said path in series with said inductance and variable condenser thereof, and of such magnitude of capacity that said path, throughout the range of adjustment of said condensers in unison, is continually tuned to series resonance for a frequency higher than the frequency of the desired signal by twice the intermediate frequency.

11. A superheterodyne receiver comprising a first detector, an input system therefor including a variable condenser, an open antenna system coupled to said input system and including a path having an inductance and a variable condenser in series, a local oscillator system having a variable condenser, an intermediate frequency amplifier, and means mechanically coupling said condensers for movement in unison to tune said input system to a desired signal frequency, to generate local oscillations whose frequency differs from the desired frequency by the intermediate frequency, and simultaneously to effect series resonance of said path for another frequency differing from the desired signal frequency by twice the intermediate frequency substantially to eliminate transfer to said input system of energy of said other frequency.

12. A superheterodyne receiver compris-

- ing a first detector, an input system therefor including a variable condenser, an open antenna system coupled to said input system and including a path having an inductance 5 and a variable condenser in series, a local oscillator, an intermediate frequency amplifier, and means mechanically coupling said condensers for movement in unison to tune said input system to a desired signal frequency and simultaneously to effect series resonance of said path for another frequency differing from the desired signal frequency by twice the intermediate frequency substantially to eliminate transfer to said input system of energy of said other frequency.
